UNITED STATES PATENT OFFICE.

WILLIAM H. VOSS, OF DAVENPORT, IOWA.

MECHANICAL MOVEMENT.

No. 843,917.

Specification of Letters Patent.

Patented Feb. 12, 1907.

Application filed October 26, 1906. Serial No. 340,676.

To all whom it may concern:

Be it known that I, WILLIAM H. VOSS, a citizen of the United States, and a resident of Davenport, in the county of Scott and State 5 of Iowa, have invented certain new and useful Improvements in Mechanical Movements for Washing-Machines, of which the following is a clear, full, and exact description.

My invention relates more particularly to 10 mechanism for actuating what is known as a "lever" washing-machine, and includes a rotary reciprocal stirrer-shaft that depends down through suitable bearings in the cover of the tub of the machine and a vertically-disposed lever for actuating said shaft, which 15 is fulcrumed in a supporting-frame attached to the top of the cover and is operated by working it back and forth. This construction takes up considerable space in a vertical 20 direction and compels the operator to stand while working the machine.

The object of my invention is to make the actuating mechanism of this kind of machine occupy less space and to enable the operator 25 to sit down while at work and to substitute a removable handle for the lever, which can be easily applied to the machine when it is desired to operate the same and as easily removed when the work is done, substantially 30 as hereinafter fully described, and as particularly pointed out in the claims.

In the drawings, Figure 1 is a vertical central section through a washing-machine, showing my improvements applied thereto. Fig. 35 2 is a plan view of the reversing mechanism removed from the machine and drawn to a larger scale. Fig. 3 is a central vertical section taken on dotted line 3 3, Fig. 2. Fig. 4 is a side elevation of said reversing mechanism, showing a portion of the double rack 40 broken away.

My invention more particularly relates to the washing-machines for which I made application for Letters Patent of the United States, 45 Serial No. 339,388, filed October 17, 1906, although it can be used with or without the mechanism therein shown for utilizing the momentum of the fly-wheel.

The tub (marked A in the drawings) is supported by several legs *a a* and is provided with a divided cover B, one segment of which is permanently secured to the top of the tub and the other portion hinged thereto, similar to that illustrated and described in the afore-

said application, (but not shown in the drawings herein.) A vertically-disposed stirrer-shaft C extends through a suitable bushing *b*, journaled in bearings in the center of the cover, and extends up through the central squared opening of a pinion E, so that it can 55 be moved vertically independent of said pinion, but will revolve therewith. Above pinion E shaft C extends up through the squared bore of a sleeve *c*, the upper end of which latter is journaled in bearings *d* in the upper end 60 of the gooseneck standard of a supporting-frame F. This supporting-frame F is provided with a base-plate by means of which it is secured to the cover, and the bearings *f*, in which the sleeve *b* is journaled, depends down 65 from the screw-plate and through the cover, substantially as shown in the drawings.

Loosely journaled upon the sleeve *c* between bearings *d* and pinion E is the boss of a horizontally-projecting segmental gear G. 70 The radius of the periphery of the teeth of this segmental gear is preferably about twice that of the teeth of the pinion E, and the gear engages a rack H, projecting toward the same from the vertical flange of a horizontal reciprocating carrier I. Carrier I consists of a longitudinally-elongated plate, which is provided at its ends with downwardly-projecting lugs *g*, that have suitable 75 squared openings in them corresponding to 80 the contours of a horizontal guide-bar *h*, on which they are mounted and slide longitudinally. The ends of this guide-bar *h* are suitably secured in short standards *j j*, made integral with the screw-plate secured to the 85 cover. The longitudinal edge of the carrier 90 I, opposite rack H, is flanged downward and provided with a rack J, which is in a plane parallel with but located below rack H, so that it can engage pinion E and transmit the 95 motion of the segmental gear G to said pinion.

The segmental gear G is operated by means of a lever K, whose inner end is provided with a suitable opening to enable it to be 100 placed over and transfixated upon the squared stud *k*, arising from the web of the segmental gear near and midway between the ends of the segmental series of teeth thereof. The inner end of this lever preferably extends 105 nearer the center of the segmental gear than stud *k* and is provided with a vertical opening thereon to enable it to be set over and

caught on a pin *m*, secured to and arising from the web of the gear practically midway between the stud and the shaft *C*. The opposite end of the lever extends out, preferably beyond the circumference of the cover of the tub, and is provided with a suitable handle *K'*, which may, as shown, arise vertically therefrom or, if desired, extend horizontally in alignment therewith.

10 The mechanism for utilizing the momentum of a balance-wheel is substantially the same as shown in the application hereinbefore referred to and consists of a link 2, which has one end pivotally connected to lugs 3, 15 arising from one end of the carrier *I*, and the other end pivotally secured in one of the series of holes in the upper end of a rocking beam 4. This rocking beam is fulcrumed to lugs 5, projecting from a suitable plate secured to the side of the tub near its bottom, and its lower end extends below the said tub a suitable distance and is connected by means of the pitman 6 to the crank-pin of a gear 7, which latter is journaled in the end of 20 a suitable hanger 8 and secured to and depending down from the bottom of the tub. The gear 7 engages a pinion 9, secured fast to the adjacent end of a drive-shaft 10, that extends horizontally a suitable distance beyond the circumference of the bottom of the tub, and has a balance or fly wheel 12 secured thereto.

In operation when the lever *K* is worked back and forth the carrier *I* is reciprocated 35 longitudinally, and through the link 2 rocking beam 4 and pitman 6 are actuated and revolve the gear 7, which latter, through its engagement with pinion 9, rotates shaft 10 and fly-wheel 12. At the same time the carrier *I*, through the engagement of its rack *J* 40 with the gear *E*, rotates the surer-shaft *C* back and forth a suitable distance, which is limited by the motion of the rocking beam 4 and in reversing is materially assisted by the momentum of the fly-wheel, and thus greatly 45 lessens the manual effort required in operating the machine.

What I claim as new is—

1. In a washing-machine the combination 50 with a rotary reciprocal shaft, of a pinion thereon through which said shaft extends and has independent longitudinal movement but revolves therewith and by which alone said shaft is actuated, a segmental gear loosely journaled on said shaft, and means connecting said segmental gear and pinion.

2. In a washing-machine the combination 55 with a rotary reciprocal shaft, of a pinion thereon by which alone said shaft is actuated, a segmental gear loosely journaled on said shaft, and means connecting said segmental gear and pinion.

3. In a washing-machine the combination 60 with a rotary reciprocal shaft, of a pinion thereon through which said shaft extends and

has independent longitudinal movement but revolves therewith, a segmental gear loosely journaled on said shaft, and a longitudinally-reciprocal rack connecting said segmental gear and pinion.

4. In a washing-machine the combination 70 with a rotary reciprocal shaft, of a pinion thereon, a segmental gear loosely journaled on said shaft, and a longitudinally-reciprocal rack connecting said segmental gear and 75 pinion.

5. In a washing-machine the combination 80 with a rotary reciprocal shaft, of a pinion thereon through which said shaft extends and has independent longitudinal movement but 85 revolves therewith, a segmental gear loosely journaled on said shaft, a handle therefor which together with said gear constitute a lever of the second class, and means connecting said segmental gear and pinion.

6. In a washing-machine the combination 90 with a rotary reciprocal shaft, of a pinion thereon, a segmental gear loosely journaled on said shaft, a handle therefor, which together with said gear constitute a lever of the 95 second class, and means connecting said segmental gear and pinion.

7. In a washing-machine the combination 100 with a rotary reciprocal shaft, of a pinion thereon through which said shaft extends and has independent longitudinal movement 105 but revolves therewith, a segmental gear loosely journaled on said shaft, a handle therefor, which together with said gear constitute a lever of the second class, and a longitudinally-reciprocal rack connecting said segmental gear and pinion.

8. In a washing-machine the combination 110 with a rotary reciprocal shaft, of a pinion thereon, a segmental gear loosely journaled on said shaft, a handle therefor, which together with said gear constitute a lever of the second class, and a longitudinally-reciprocal 115 rack connecting said segmental gear and pinion.

9. In a washing-machine the combination 120 with a rotary reciprocal shaft, of a pinion thereon through which said shaft extends and has independent longitudinal movement but 125 revolves therewith, a segmental gear loosely journaled on said shaft, and a longitudinally-reciprocal double rack having parallel series of teeth and adapted to engage both said segmental gear and pinion.

10. In a washing-machine the combination 130 with a rotary reciprocal shaft, of a pinion thereon, a segmental gear loosely journaled on said shaft, and a longitudinally-reciprocal double rack having parallel series of teeth and adapted to engage both said segmental gear and pinion.

11. In a washing-machine the combination 135 with a rotary reciprocal shaft, of a pinion thereon through which said shaft extends and has independent longitudinal movement

but revolves therewith, a segmental gear loosely journaled on said shaft, and a longitudinally-reciprocal rack having parallel series of teeth and adapted to engage both said segmental gear and pinion.

12. In a washing-machine the combination with a rotary reciprocal shaft, of a pinion thereon, a segmental gear loosely journaled on said shaft, and a longitudinally-reciprocal double rack having parallel series of teeth and adapted to engage both said segmental gear and pinion.

13. In a washing-machine the combination with a rotary reciprocal shaft, of a pinion thereon through which said shaft extends and has independent longitudinal movement but revolves therewith, a segmental gear loosely journaled on said shaft, a handle therefor which together with said gear constitute a lever of the second class, and a longitudinally-reciprocal double rack having parallel series of teeth and adapted to engage both said segmental gear and pinion.

14. In a washing-machine the combination with a rotary reciprocal shaft, of a pinion thereon, a segmental gear loosely journaled on said shaft and handle therefor, which together with said gear constitute a lever of the second class, and a longitudinally-reciprocal double rack having parallel series of teeth and adapted to engage both said segmental gear and pinion.

15. In a washing-machine the combination with a rotary reciprocal shaft, of a pinion thereon through which said shaft extends and has independent longitudinal movement but revolves therewith, a segmental gear loosely journaled on said shaft, a handle therefor, which together with said gear constitute a lever of the second class, and a longitudinally-reciprocal double rack having parallel series of teeth and adapted to engage both said segmental gear and pinion.

16. In a washing-machine the combination with a rotary reciprocal shaft, of a pinion thereon, a segmental gear loosely journaled on said shaft, a handle therefor, which together with said gear constitute a lever of the second class, and a longitudinally-reciprocal double rack having parallel series of teeth and adapted to engage both said segmental gear and pinion.

teeth and adapted to engage both said segmental gear and pinion.

17. In a washing-machine the combination with a rotary reciprocal shaft, a pinion thereon and revoluble therewith, and a segmental gear loosely journaled on said shaft, of a longitudinally-reciprocal carrier having a longitudinal rack near one longitudinal edge thereof engaging said segmental gear and a longitudinal rack near its opposite longitudinal edge 55 engaging said pinion.

18. In a washing-machine the combination with a rotary reciprocal shaft, a pinion thereon and revoluble therewith, and a segmental gear loosely journaled on said shaft, 65 of a longitudinally-reciprocal carrier having a longitudinal rack above it near one longitudinal edge thereof engaging said segmental gear and a longitudinal rack below and near its opposite longitudinal edge 60 engaging said pinion.

19. In a washing-machine the combination with a rotary reciprocal shaft, a pinion thereon revoluble therewith, and a segmental gear loosely journaled on said shaft, and a 75 handle which together with said gear constitute a lever of the second class, of a longitudinally-reciprocal carrier having a longitudinal rack near one longitudinal edge thereof 70 engaging said segmental gear and a longitudinal rack near its opposite longitudinal edge 80 engaging said pinion.

20. In a washing-machine the combination with a rotary reciprocal shaft, a pinion thereon and revoluble therewith, a segmental gear loosely journaled on said shaft, and a handle which together with said gear constitute a lever of the second class, of a longitudinally-reciprocal carrier having a longitudinal rack above it near one longitudinal edge 85 thereof 90 engaging said segmental gear and a longitudinal rack below and near its opposite longitudinal edge engaging said pinion.

In testimony whereof I have hereunto set my hand and seal this 18th day of October, 95
A. D. 1906.
